INTERLOCKING FLOORING PANEL

David L. Kiner, Columbus, Ohio, assignor to United
McGill Corporation, Columbus, Ohio

Filed Apr. 1, 1971, Ser. No. 130,177

Term of patent 14 years

Int. Cl. D25—02

U.S. Cl. D13—1

FIG. 1

FIG. 2

FIG. 3

FIG. 4 is a vertical sectional view taken along line 4-4 of FIG. 2.

FIG. 5 is a perspective view of a section of a modified interlocking flooring panel embodying this invention.

FIG. 6 is an end elevational view of the floor panel shown in FIG. 5.

The panel is broken away in FIG. 1 to indicate indeterminate length.

FIG. 1 is a perspective view of an interlocking flooring panel embodying this invention.

FIG. 2 is a top plan view on an enlarged scale of a portion of the panel shown in FIG. 1 but taken intermediate the ends thereof.

FIG. 3 is a vertical sectional view taken along line 3-3 of FIG. 2.

FIG. 4 is a vertical sectional view taken along line 4-4 of FIG. 2.

FIG. 5 is a perspective view of a section of a modified interlocking flooring panel embodying this invention.

FIG. 6 is an end elevational view of the floor panel shown in FIG. 5.

The panel is broken away in FIG. 1 to indicate indeterminate length.

I claim:

The ornamental design for an interlocking flooring panel, substantially as shown and described.
